CLAIM

The ornamental design for a surgical staple, as shown and described.

DESCRIPTION

FIG. 1 is a front perspective view of a first embodiment of our new surgical staple;

FIG. 2 is a top plan view of the surgical staple of FIG. 1; FIG. 3 is a bottom plan view of the surgical staple of FIG. 1;

FIG. 4 is a front side elevational view of the surgical staple of FIG. 1, the rear side elevational view being identical; FIG. 5 is a right side elevational view of the surgical staple of FIG. 1, the left side elevational view being identical; FIG. 6 is a front perspective view of a second embodiment of our new surgical staple;

FIG. 7 is a top plan view of the surgical staple of FIG. 6; FIG. 8 is a bottom plan view of the surgical staple of FIG. 6;

FIG. 9 is a front side elevational view of the surgical staple of FIG. 6, the rear side elevational view being identical; and, FIG. 10 is a right side elevational view of the surgical staple of FIG. 6, the left side elevational view being identical.

Portions of the surgical staples shown in dash-dash-dash broken lines in the figures form no part of the claimed design. The dash-dot-dash broken lines depict boundaries of the claimed design.

1 Claim, 8 Drawing Sheets
